US0D1035436S

(12) **United States Design Patent** (10) **Patent No.:** **US D1,035,436 S**
(45) **Date of Patent:** ** *Jul. 16, 2024

(54) **PACKAGING**

- (71) Applicant: **Regeneron Pharmaceuticals, Inc.**,
Tarrytown, NY (US)
- (72) Inventors: **Andrew Cook**, Troy, NY (US); **Victor Bradford**, Troy, NY (US); **Jason Smith**, Latham, NY (US); **Sibgat Ulla**, Rensselaer, NY (US)
- (73) Assignee: **Regeneron Pharmaceuticals, Inc.**,
Tarrytown, NY (US)
- (*) Notice: This patent is subject to a terminal disclaimer.

(**) Term: **15 Years**

(21) Appl. No.: **29/851,365**

(22) Filed: **Aug. 26, 2022**

(51) LOC (14) Cl. **09-03**

(52) U.S. Cl.

USPC **D9/424; D9/737**

(57) **CLAIM**

The ornamental design for packaging, as shown and described.

DESCRIPTION

FIG. 1 is a bottom, rear, right perspective view of a first embodiment of a packaging showing our new design; FIG. 2 is a bottom, rear, left perspective view thereof; FIG. 3 is a rear elevation view thereof; FIG. 4 is a front elevation view thereof; FIG. 5 is a left side view thereof; FIG. 6 is a right side view thereof; FIG. 7 is a bottom plan view thereof; FIG. 8 is a top view thereof; FIG. 9 is a bottom, rear, right perspective view of a second embodiment of a packaging showing our new design; FIG. 10 is a bottom, rear, left perspective view of the second embodiment; FIG. 11 is a rear elevation view of the second embodiment; FIG. 12 is a front elevation view of the second embodiment; FIG. 13 is a left side view of the second embodiment; FIG. 14 is a right side view of the second embodiment; FIG. 15 is a bottom plan view of the second embodiment; and, FIG. 16 is a top view of the second embodiment.

The broken lines of even length shown in the drawings illustrate portions of the packaging that form no part of the claimed design.

1 Claim, 10 Drawing Sheets
